UNITED STATES PATENT OFFICE.

BENJAMIN F. BAIN, OF PITTSBURGH, PENNSYLVANIA.

MECHANICAL MOVEMENT.

1,286,494.

Specification of Letters Patent.

Patented Dec. 3, 1918.

Application filed January 11, 1918. Serial No. 211,342.

To all whom it may concern:

Be it known that I, BENJAMIN F. BAIN, a citizen of the United States, residing at Pittsburgh, in the county of Allegheny and 5 State of Pennsylvania, have invented certain new and useful Improvements in Mechanical Movements, of which the following is a specification.

The invention relates to mechanical movements and is designed particularly for use 10 with toys, although capable of use in other relations. It has for its primary object; the provision of an improved movement of simple cheap construction adapted to convert 15 oscillatory movement as imparted to a rotatable element into continuous forward rotary movement. Certain embodiments of the invention are illustrated in the accompanying drawings, wherein—

20 Figure 1 is a partial plan view and partial section through one embodiment of the invention; Fig. 2 is a front elevation of the bearing member which carries the main axle of the driving means; Fig. 3 is a front elevation 25 of the apparatus when the driving member is in one position of lateral movement; Fig. 4 is a view similar to that of Fig. 3 but with the driving member in its other position of lateral movement; Figs. 5 and 6 30 are front elevations of modified constructions; Fig. 7 is a view similar to that of Fig. 1 of another modification; and Fig. 8 is a diagrammatic front view illustrating still another modification.

35 The particular embodiment of the invention as shown in Figs. 1 to 4 is designed for use in connection with a toy having a marble operating means adapted to discharge marbles to a basket or container carried by one 40 end of a cord which passes over the driving wheel, such cord having a counterweight at its other end. The marbles are intermittently discharged into the basket, causing it to move down after which there is an automatic discharge and the counterweight returns 45 the basket to its original position. This back and forth movement of the cord gives the driving wheel an intermittent oscillatory movement, and the mechanism as 50 illustrated constitutes the means for converting this oscillatory movement into a continuous forward movement, such continuous forward movement being imparted to a wind mill or other device, such as indicated 55 at A in dot-and-dash lines. It will be un-

derstood, however, that the mechanical movement is not limited to this particular application but may be used in any device where it is desired to transform oscillatory movement into continuous forward rotary 60 movement by some driven member.

Referring to the construction shown in Figs. 1 to 4, the reference numeral 1 indicates the driving wheel over which passes the cord 2 carrying at one end the receiving 65 basket or receptacle and at the other end the counterweight 3. This driving wheel is carried by an axle 4 mounted with a loose running fit at its rear end in the upstanding bearing member 5 and at its front end in the 70 upstanding bearing member 6, such member 6 being shown in front elevation in Fig. 2. A slot 7 is provided in the bearing member 6 so that the axle and the driving wheel carried thereby may move laterally a limited 75 distance. The bearing members 5 and 6 in the construction shown, which is relatively light and cheap, constitute integral parts of the sheet metal member 8 which is secured in any suitable manner to the base 9. 80

The driving wheel 1 is preferably also made of sheet metal and is provided with the forwardly projecting annular flange 10. Mounted inside this flange 10 are the intermeshing gears 11 and 12 which may also be 85 made of sheet metal stamped to the shape as indicated in Figs. 1 and 3. These gears 11 and 12 are carried by the axles 13 and 14 mounted in the bearing members 15 and 16 preferably made of sheet metal and secured 90 to the base in the same manner as the member 8. The axle 13 carries the wind mill A or other device which it is desired to rotate forward continuously.

95 The flange 10 of the driving wheel constitutes a frictional driving means for the gears 11 and 12, and is of such diameter, as indicated in Fig. 3, that when it is in engagement with one of the gears, such as 11, it is out of engagement with the other gear 12. Fig. 3 illustrates the position of the parts when the counterweight 3 is moving down, thus rotating the driving wheel 1 in a clockwise direction. At this time the flange 10 engages the periphery of the gear 11 and is out of engagement with the gear 12. This rotates the gear 11 and the wind mill A in a clockwise direction. The position of the wheel 1 is due to the mounting 100 of the axle 4 in the bearing slot 7 so that as 105 110

the wheel 1 rotates in a clockwise direction the axle rolls to the right-hand end of the slot 7.

If the direction of movement of the cord 5 is now reversed and the basket moves down pulling the counterweight up, the wheel 1 is rotated in a counter-clockwise direction, the parts assuming the position shown in Fig. 4. At this time the flange 10 of the 10 driving wheel engages the periphery of the gear 12 driving it in a counter-clockwise direction. This causes a movement in a clockwise direction of the gear 11 which is now out of engagement with the flange 10. 15 In this case the axle 4 rolls to the left-hand end of the slot 7 (Fig. 2) carrying the wheel 1 to the left. It will therefore be seen that regardless of the direction of rotation of the wheel 1, the gear 11 and its shaft 13 are always rotated in a clockwise direction so that the wind mill or other driven device continues its forward movement when the counter-weight is coming up as well as when it is going down and there is a substantially 25 continuous drive since the period in which the driving wheel 1 is being shifted laterally is comparatively slight.

Fig. 5 illustrates a modification in which the driving wheel 17, which is operated from 30 the cable 18 is provided with a flange having the internal teeth 19. A pair of intermeshing gears 20 and 21 are employed and the construction is in other respects similar to that of Fig. 1, with the exception of the 35 gear teeth 19, which serve to make the drive more positive than is the case in the apparatus of Fig. 1, where the driving engagement between the flange and the gears is frictional.

40 Fig. 6 illustrates another modification wherein the driven gears 22 and 23 are external with respect to the drive wheel 24 instead of being internal. The wheel 24 is driven by the cable 25 and is mounted as in 45 the construction of Fig. 1, so that a limited lateral movement is possible. The wheel is provided with a driving gear 26 adapted to engage frictionally either the gear 22 or the gear 23. The gears 22 and 23 are shown as 50 being in frictional engagement with each other. It will be seen that the gear 22 is always driven in the same direction regardless of the direction of movement of the wheel 24, such wheel shifting backward and forward depending upon the direction of movement of the cable.

Fig. 7 illustrates still another modification in which the driving wheel 27 is provided with an annular flange 28 adapted to 60 frictionally engage a gear 29. The wheel 27 is mounted upon an axle 30 which axle is carried in the two bearing members 31 and 32, the first of which is slotted as indicated at 33 in order to permit the axle and 65 driving wheel to move laterally. The gear

29 is mounted upon a shaft 34 carried in the bearing members 31 and 32, such shaft being provided with the paddle wheel or other member which it is desired to drive. As the drive wheel 27 rotates in one direction its axle will roll in the bearing 33, to the position shown so that its flange 28 engages the gear 29, thus causing a forward rotation of the paddle wheel B. On the reverse movement of the wheel 27 the axle 30 70 will roll to the left-hand end of the slot 33 thus carrying the flange 28 out of engagement with the gear 29 so that the paddle wheel B continues to rotate forwardly due to its momentum. The application of driving force is thus intermittent instead of substantially continuous as in the other constructions heretofore described, but the device is somewhat cheaper than that of Fig. 1 and is sufficient for the purpose in a toy 80 since any slowing up of the driven part is hardly perceptible.

Fig. 8 illustrates still another modification in which 35 is the flanged driving wheel having integral therewith a forwardly projecting driving gear 36. 37 is the driven wheel corresponding to the wheel 11 in Fig. 1. Upon the movement of the wheel 35 in a clockwise direction the flange of the drive wheel is brought into engagement with the 90 gear 36 driving it in a clockwise direction. When the movement of the wheel 35 is reversed, the wheel shifts to the left carrying the gear 36 into engagement with the gear 37 and carrying the flange of the wheel out 100 of engagement with the gear 37. Under these conditions the gear 37 will still be driven in a clockwise direction. The wheel 35 is of course mounted for lateral movement just as in the construction of Fig. 1. 105 Other modifications of the invention might be made without departing from the broad principle thereof, which principle involves the mounting of the driving wheel so that it will roll laterally to make or break driving engagement with a rotary driven member depending upon its direction of rotation. It will also be understood that the invention applies equally well to an intermittent drive such as that of Fig. 7 or to one in which 110 the driving force is applied substantially continuously as in the other forms of device illustrated.

What I claim is:

1. In combination, a rotatable driving element, an axle therefor, means for imparting oscillatory movement to said element, a bearing for the axle, elongated laterally and arranged so that the axle of the driving element may freely move therein laterally back 125 and forth as said element oscillates, and a rotatable driven element adapted to be engaged by the driving element when such element is in one position of lateral movement and disengaged therefrom when the driving 130

element is in its other position of lateral movement, whereby said driven element has continuous forward rotary movement.

2. In combination, a rotatable driven element, a slotted bearing, a rotatable driving element having an axle mounted in said slotted bearing for limited lateral movement bodily therein, and means constructed and arranged to have opposed directional rotation and to impart it to said driving element, said axle adapted to roll laterally toward one side of the bearing to effect an engagement between said elements when the driving element is rotated in one direction by said means, and to roll laterally toward the other side of the bearing and assume its other extreme of lateral movement to effect a disengagement of said elements when the driving element is rotated the opposite direction by said means, the rolling movement of the axle in the bearing being automatic under the influence of said means.

3. In combination, a rotatable driving element having an axle, a support for the axle, a portion of said support formed with an elongated horizontal slot in which the axle is positioned for free lateral movement relative the support, a rotatable driven element, and a means having opposite direction rotation including a flexible member operatively associated with said driving element, whereby the axle is caused to roll laterally toward one side of the slot so as to bring the elements into operative engagement when said member is in one direction of move-

ment, and to roll toward the other side of the slot upon opposite directional rotation of said member and thereby effect a disengagement of said elements, substantially as and for the purpose set forth.

4. In combination, a support having a slotted bearing, rotatable driving means having an axle mounted in said bearing for limited lateral movement bodily, means for imparting oscillatory movement to said rotatable driving means, said axle adapted to roll laterally and freely in one direction toward one side of the slotted bearing when the driving means is rotated in one direction by said oscillatory means and laterally in the other direction when the driving means is rotated reversely, and driven means positioned so that one part thereof is in engagement with one part of the driving means and is driven forwardly thereby when the driving means is in one position of lateral movement, and whereby another part of the driven means is in engagement with the driving means and is also driven forwardly thereby when the driving means is in its other position of lateral movement, the lateral movement of the driving means in either direction which carries it into engagement with one part of the driven means simultaneously and automatically carrying it out of engagement with the other part of the driven means as the driving means oscillates.
